Primary Examiner — Susan Bennett Hattan*Assistant Examiner* — Janice Hallmark(57) **CLAIM**

The ornamental design for a mobile device cradle, as shown and described.

DESCRIPTION

FIG. 1 is an elevated right side perspective view of a mobile device cradle showing my new design;

FIG. 2 is an elevated left side perspective thereof;

FIG. 3 is a front elevation view thereof;

FIG. 4 is a top plan view thereof;

FIG. 5 is a bottom plan view thereof;

FIG. 6 is a left side view thereof; and,

FIG. 7 is a right side view thereof.

The broken lines in the drawings depict environmental subject matter only and form no part of the claimed design.
